UNITED STATES PATENT OFFICE.

ELMER HARROLD, OF LEETONIA, OHIO.

CUTTER-HEAD.

948,540.

Specification of Letters Patent. Patented Dec. 14, 1909.

Application filed August 11, 1909. Serial No. 512,398.

To all whom it may concern:

Be it known that I, ELMER HARROLD, a citizen of the United States, residing at Leetonia, in the county of Columbiana and State of Ohio, have invented certain new and useful Improvements in Cutter-Heads, of which the following is a specification.

The present invention relates more particularly to rotary cutter heads for jointers, 10 planers and similar wood working machines, and the principal object is to provide novel, simple and highly effective means for securing the cutter blades in place in the head or body, said means not only securely holding the blades, but being also itself held against accidental displacement.

Two embodiments of the construction are illustrated in the accompanying drawings, wherein:

20 Figure 1 is a view in elevation of a head or rotary cutter, showing the preferred embodiment of the invention. Fig. 2 is an end elevation partially in section on the line 2—2 of Fig. 1. Fig. 3 shows detail views of one 25 of the wedges. Fig. 4 is a view in elevation of a portion of a modified form of construction. Fig. 5 is a detail perspective view of the wedge member, forming a part of this modification. Fig. 6 is a detail view of the 30 holding bar 10, showing a modification of the means for adjusting the cutter blade 9. Fig. 7 is a detail view showing the application of this modification.

Similar reference numerals designate corresponding parts in all the figures of the drawings.

In the embodiment disclosed in Figs. 1-3 inclusive, the body 6 of the head or cutter is substantially of the usual shape, and has 40 a plurality of cutter-blade receiving seats 7, with outwardly tapered sockets 8 communicating with the seats, a plurality of these sockets being associated with each seat throughout the length of the head. Arranged in each seat is a cutter blade 9 and a throat-piece 10, constituting a holding bar for the cutter, and may also have a flange portion 11 arranged beneath the blade, which flange portion may, in turn, be provided 50 with blade-adjusting screws 12 bearing against the inner edge of the blade.

A very compact and rigid construction is provided by having the holding bar or throat piece 10 of substantially an L-shape in 55 cross-section with the knife blade solidly seated within and against said bar. Also

the various elements constituting the fastening are rendered more effective and less liable to displacement by having the knife-receiving seat disposed substantially tangentially to the axis of the body, and the outwardly tapered socket lying in a plane substantially radial to the axis of the body. 60

Arranged in each of the sockets 8, is an outwardly tapered wedge-block 13 having a 65 threaded bore therethrough, as shown at 14, to receive a thrust screw 15 screwed through said bore and bearing against the bottom of the socket. This screw has an angular recess 16 to receive an actuating tool. In the 70 construction of this device, the sockets 8 are first drilled into the body and the seat 7 then milled therein, said seat being disposed tangentially and cutting through the sockets, as shown. It will be obvious that the blade 75 can be readily placed in position, and when in place, can be securely fastened by turning the thrust screws 15, which will move the wedge blocks outwardly, thus causing the holding bar to clamp firmly against the 80 blade.

A slight modification of the structure is illustrated in Figs. 4 and 5. In this form of construction, the body is designated 17, and is provided with a seat to receive the cutting blade 18, and the throat-piece or holding bar 19. Instead of a plurality of wedge bar 20 is employed, as shown in Fig. 5, and is provided with a plurality of threaded 85 openings 21 that receive thrust screws 22. The socket in this instance extends the entire length of the body, and it will be obvious that by rotating the thrust screws 22, the wedge bar or block 20 will be forced 90 outwardly, effecting the same clamping action as above described. Also a slight modification of the means for adjusting the cutter-blade 9 may be had by providing the holding bar 10 with two or more series of 100 pin holes 23, diagonally disposed on the face of the bar, to receive the pins 24, against which the back edge of the cutter blade may rest, as shown in Figs. 6 and 7. It is obvious that with this arrangement the blade 105 may be readily adjusted by advancing the pins 24 forward in the pin holes 23 as the cutter blade is worn away.

From the foregoing, it is thought that the construction, operation and many advantages of the herein described invention will 110 be apparent to those skilled in the art with-

out further description, and it will be understood that various changes in the size, shape, proportion and minor details of construction may be resorted to without departing from the spirit, or sacrificing any of the advantages of the invention.

Having thus fully described my invention, what I claim as new and desire to secure by Letters-Patent, is:—

- 10 1. In a structure of the character set forth, the body having a knife-receiving seat disposed substantially tangential to the axis of the body, a knife blade located in said seat, a holding bar arranged in the seat alongside of the knife blade, said body also having an outwardly tapered socket lying in a plane substantially radial to the axis of the body, an outwardly tapered wedge-block located in the socket and bearing against the bar, and means carried by the block for forcing the latter in an outward direction to wedge it between the holding bar and one wall of the socket.
- 15 2. In a structure of the class described, the combination of a body having a longitudinal knife-receiving seat disposed substantially tangential to the axis of the body, and a plurality of sockets opening into said seat and lying in a plane substantially radial to the axis of the body, a holding bar arranged in the knife seat, a knife blade seated within and against the holding bar, a plurality of

clamping wedges located in the sockets and each having a flat side bearing against the holding bar, and thrust screws threaded through the wedges and stepped against the bottoms of the sockets.

3. In a structure of the character described, the combination with a body having a knife-receiving seat and the knife blade therein, of a throat piece arranged in the seat at one side of the blade and having a flange portion underlying the inner edge of the knife blade, and blade adjusting means carried by said flange portion, and fastening means for the throat piece.

4. In a structure of the character set forth, the combination with a body having a knife-receiving seat and a plurality of sockets opening into the seat, of a knife arranged in the seat, a holding bar also arranged in the seat and provided with laterally-extending adjustably-mounted knife adjusting pins, a plurality of clamping wedges located in the sockets and having flat sides bearing against the holding bar, and thrust-screws threaded through the wedges and bearing against the bottoms of the sockets.

In testimony whereof I hereunto affix my signature in the presence of two witnesses.

ELMER HARROLD.
